UNITED STATES PATENT OFFICE

GEORGE W. CASSIDY, OF FLUSHING, NEW YORK

REFLECTOR FOR PORTABLE LAMPS

Application filed December 16, 1930. Serial No. 502,640.

My invention relates to that class of lamps which are known as direct and indirect, and is suitable for use on either floor or table lamps.

5 My invention has for its object to provide a construction in which the reflector will be supported in a one-piece housing which also acts as a housing for the sockets for the direct illumination.

10 My invention has for its further object to provide a chamber in the housing for the wires which convey the current whereby they will be invisible to the eye.

15 My invention has for its further object to construct the housing in which the plurality of sockets for the direct illumination are mounted so small that when lamps of 25 or 40 watt size are used they will be far enough away from the shade to permit a satisfactory 20 diffusion to light and will also eliminate excessive brightness or spotlight effects on the shade.

25 My invention has for a further object to provide a device which can be quickly and easily installed in place.

A further object is to provide a housing constructed so that it will act as a holder for a mirror or other type of reflector and which will also provide means for supporting a 30 shade holder and also act as an eye shield eliminating any direct rays from the main lamp and reflector.

35 My means of accomplishing the foregoing objects may be more readily understood by having reference to the accompanying drawings which are hereunto annexed and are a part of this specification in which—

40 Fig. 1 is a side elevation partly broken away, showing the interior of the reflector;

45 Fig. 2 is a vertical sectional view, some of the parts being shown in elevation;

Fig. 3 is an enlarged detail view of the intermediate portion of the housing; and

Fig. 4 is a vertical sectional view of the detail view as shown in Fig. 3.

Similar reference numerals refer to similar parts throughout the entire description.

As shown in the drawings, the main lamp bulb 1 is mounted in a socket 2 which is carried by a nipple 3 mounted in an opening 4

in the center of the lower part of the housing. This housing consists of an upwardly and outwardly flaring portion 5, an intermediate vertical cylindrical portion 6 and a lower portion 7 which tapers inwardly and is suitably attached to the intermediate portion 6. A reflector 8, which may be provided with a mirror or other suitable reflecting surface, is mounted inside of the upper portion 5 of the housing. As will be clearly seen from the drawings this portion 5 of the housing is provided with a vertical cylindrical portion 9, at its top, the edge of which acts as a support for the shade holder (not shown) and also prevents any direct rays' light, emanating from the bulb, from reaching the eye of an observer.

55 In the intermediate portion 6 I provide a plurality of sockets 10 which are provided with the usual threads 11 with the reception 60 of electric light bulbs 12 of standard construction. These sockets are suitably connected by electric current conductors which lead to a standard switch 13 which is secured to the vertical wall 14 of the intermediate 65 portion 6. A chain pull 15 of the usual construction provides means for turning on the lights in these sockets. An opening 16 is formed in the socket 2 for the introduction of the current carrying conductors 17 and 18 70 to convey the current from a source of supply (not shown) to the switch 13. The socket 2 is provided with a chain pull 19 of standard 75 construction, the chain passing through the opening 20 formed in the lower part 7 of 80 the housing. The end 21 of the nipple 3 may be screwed into a tubing 22, a fragmentary portion of which only is shown in the drawings. This tubing may be a standard of any 85 type of portable lamp. It will be apparent 90 from an inspection of the drawings and the hereinbefore contained description that I have produced a reflector for indirect lamps which obtains all of the objects set forth and enables me to produce a device in which all 95 of the exposed parts are so constructed that the same may be finished exactly as the other metal parts of the supporting lamp, either floor or table, as the case may be.

Having described my invention what I re- 100

gard as new and desire to secure by Letters Patent of the United States, is:

In a device of the character described, a one-piece reflector, shade, and socket support formed of opaque material, comprising an upper outwardly flaring portion, an intermediate vertical cylindrical portion, a lower inwardly tapering portion, a socket mounted in said lower portion, means to secure said socket to a portion of said housing, a reflector mounted in the upper portion of said support, an electric lamp bulb mounted in said socket, a chain pull for said socket which is accessible from the exterior of said support, a plurality of electric lamp sockets mounted in said vertical cylindrical portion, a switch mounted therein operable from the exterior of said cylindrical portion, and conductors to convey electric current from said switch to said sockets, there being a chamber in said intermediate portion in which said conductors are mounted.

GEORGE W. CASSIDY.
